(57) **CLAIM**

The ornamental design for a DIN rail module, as shown and described.

DESCRIPTION

FIG. 1 is a side perspective view of a first embodiment of a DIN rail module showing our new design;

FIG. 2 is an opposite side perspective view thereof;

FIG. 3 is a side view thereof;

FIG. 4 is an opposite side view thereof;

FIG. 5 is a bottom view thereof;

FIG. 6 is a top view thereof;

FIG. 7 is a front view thereof;

FIG. 8 is a back view thereof;

FIG. 9 is a perspective view thereof shown with environment;

FIG. 10 is another perspective view thereof shown with environment;

FIG. 11 is another perspective view thereof shown with environment;

FIG. 12 is another perspective view thereof shown with environment;

FIG. 13 is a side perspective view of a second embodiment of the DIN rail module showing our new design;

FIG. 14 is an opposite side perspective view thereof;

FIG. 15 is a side view thereof;

FIG. 16 is an opposing side view thereof;

FIG. 17 is a bottom view thereof;

FIG. 18 is a top view thereof;

FIG. 19 is a front view thereof;

FIG. 20 is a back view thereof;

FIG. 21 is a perspective view thereof shown with environment;

FIG. 22 is another perspective view thereof shown with environment;

FIG. 23 is another perspective view thereof shown with environment; and,

FIG. 24 is another perspective view thereof shown with environment.

(Continued)

The short-long spaced broken lines immediately adjacent the shaded areas represent the bounds of the claimed design while all other broken lines are directed to environment and are for illustrative purposes only; the broken lines form no part of the claimed design.
